CLAIM

The ornamental design for a combination storage tray and case for compact discs, as shown and described.

DESCRIPTION

FIG. 1 is a perspective view of a combination storage tray and case for compact discs showing my new design;

FIG. 2 is an exploded perspective view thereof;

FIG. 3 is a perspective view of FIG. 1, the lid shown in an open position;

FIG. 4 is a bottom plan view of FIG. 1;

FIG. 5 is a rear elevational view of FIG. 1;

FIG. 6 is a right side elevational view of FIG. 1;

FIG. 7 is a top plan view of FIG. 1;

FIG. 8 is a left side elevational view of FIG. 1; and,

FIG. 9 is a front elevational view of FIG. 1.

FIG. 1

FIG. 2
